ATTORNEY

UNITED STATES PATENT OFFICE.

JOHN R. WOOD, OF IRVINGTON, NEW JERSEY, ASSIGNOR TO NEW PROCESS MULTI-CASTINGS COMPANY, OF NEWARK, NEW JERSEY, A CORPORATION OF NEW JERSEY.

PROCESS OF MAKING MATCHED-PATTERN PLATES.

Application filed September 19, 1923. Serial No. 663,535.

To all whom it may concern:

Be it known that I, JOHN R. WOOD, a citizen of the United States of America, residing at Irvington, in the county of Essex and 5 State of New Jersey, have invented certain new and useful Improvements in Processes of Making Matched-Pattern Plates, of which the following is a full, clear, and exact description.

10 In the process of molding by the use of sand in flasks, one of the commonly practiced ways of obtaining the molds is by the use of matched plates, or two separate face plates, one for the drag, the other for the cope member of the flask. These plates it is very difficult to produce in a form in which they exactly match so that they are expensive and when obtainable do not produce perfect castings.

15 The invention which forms the subject of my present application for Letters Patent resides in a novel and economical method of obtaining these two matched plates from one and the same mold, and in order to convey a clear understanding of how I accomplish this I may describe in somewhat general terms the process which I follow—

In carrying out the invention I construct two flasks which are exact counter parts, 30 each composed of a drag and a cope member which are interchangeable, and for convenience in illustration I shall hereinafter refer to these members as the No. 1 and the No. 2 drags and the No. 1 and the No. 2 35 copes.

The first step in the process is by the use of a follow board with a pattern thereon and laid over the upper joint of an inverted drag flask member to form by ramming in any known way the No. 1 drag, in order to obtain in sand the impression of the pattern below the parting line. The sand is then struck off even with the joint and a bottom board attached to the drag member 45 which is then inverted.

With this drag, with the pattern therein, but with the follow board removed, No. 1 cope member is then associated and removed, after the parting lines have been gone over to see that they accord with the pattern. This cope member will give the impression of the pattern above the parting lines in the sand and it is then removed and set aside,

care being taken not to disturb or patch the mold as otherwise there would not result a 55 perfect match.

I then take No. 2 cope member and associate it with No. 1 drag member and fill it with sand and ram it sufficiently. It is then removed and dressed, if need be, as this does 60 not change any impression desired in the drag member No. 1.

I then place the pattern in the sand of No. 1 cope member and associate with it No. 2 drag member and ram the same dressing it, if so desired, and then separate the two members removing the pattern from the cope. There will thus be produced two drag members, No. 1 of which gives the exact impression of the pattern below the parting 70 line, and two cope members, No. 1 of which gives the exact impression of the pattern above the parting line.

I then lay over the sand of No. 1 drag a pattern frame and over the edges of the joint strips of exactly the same thickness as said pattern frame. Between these strips and the edges of the frame there will remain empty spaces and these are then filled and packed with sand to the level of the top of 75 the strips and the pattern frame then removed or lifted from the mold.

No. 2 cope is then associated with No. 1 drag with the interposed strips and a complete mold will thus be formed which, when 80 poured, will produce a drag plate with an exact copy of all parts of the original pattern below the parting line.

In the same way a pattern frame or plate is placed on the sand of No. 1 cope and strips of exactly the same thickness as said frame laid on the edges, the spaces between said strip and the frame packed and levelled off, the frame lifted and the two flask members associated to form a mold which, when 90 poured, gives a cope plate with an exact copy of all parts of the original pattern 95 above the parting line.

In this way there are produced two separate matched plates both taken from one mold, each giving the exact reproduction 100 of the corresponding faces of the pattern used. These plates may be used with any kind of flask, but preferably with the two parts of a flask which, after being rammed by or on a power molding machine, may be 105

brought together as cope and drag and then stripped from the molded sand and used for making other molds.

No practical way has ever been devised 5 heretofore, so far as I am aware, for making these matched pattern parts or plates from one and the same mold, but it is manifest from the above that the two plates which I produce are perfectly matched and 10 may be used to produce perfect castings in any of the ways now known to the molder's art.

To illustrate so much of the above described process as I believe to be necessary 15 in view of the present knowledge on the part of those skilled in the art, I have attached hereto a drawing in which—

Fig. 1 shows in section the two members 20 of a flask with the pattern therein, and which may be considered as No. 1 cope and No. 1 drag.

Fig. 2 is a similar view of what may be considered as No. 2 cope and No. 1 drag associated with the edge strips between the 25 two, and the space left by the removal of the pattern frame.

Fig. 3 is a similar view under similar conditions of No. 2 drag and No. 1 cope associated.

Fig. 4 is a plan view of a frame to be interposed between the two members and

Fig. 5 is a sectional view of Fig. 2 showing the top of the sand mold in its finished condition for pouring.

The plates 1 are made of exactly the proper dimensions for the flask or flasks with which they are to be used and have ears 2 with perforations to fit over pins in the sides or edges of the flask. The copes 3 and drags 4 are in all respects similar to those now or heretofore in use and they are made up for use in any of the ways known in the art. In Figs. 2 and 3 the side or edge strips are designated by 5; the sand fillings between said strips and the edges of the pattern frames 6 are indicated by 7 and the pattern by 8.

From the description above given it is thought that no further explanation of the process or of the manner of carrying it out 50 is required. Of course in practicing the invention a practical or skilled molder will use numerous appliances and perform several operations which I have not deemed it necessary to set forth in any greater detail 55 than I have.

What I claim is—

1. The method herein described of producing matched pattern plates which consists in preparing a drag and a cope flask 60 member containing, in sand, the exact impression of the pattern below and above the parting line respectively, forming from these members and the pattern supplemental drag and cope members, and associating 65 the original drag with the supplemental cope, and the original cope with the supplemental drag spaced to an amount equal to the thickness of the plate desired and obtaining from such molds the finished 70 matched plates.

2. The method herein described of producing matched pattern plates which consists in preparing a drag and a cope flask member containing, in sand, the exact impression of the pattern below and above the parting line respectively, forming from these members and the pattern supplemental drag and cope members, laying on the sand around the impressions in the original 80 member pattern frames of the desired thickness and on the edges of the flask members strips of the same thickness as the said frames, filling the spaces between said strips and the frame with sand, withdrawing 85 the pattern frames, and associating the original drag with the supplemental cope and the original cope with the supplemental drag, and obtaining from the molds thus produced the finished matched pattern 90 plates.

In testimony whereof I hereto affix my signature.

JOHN R. WOOD.
